UNITED STATES PATENT OFFICE.

LEWIS WARRINGTON CHUBB, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

Application filed May 24, 1921. Serial No. 472,055.

To all whom it may concern:

Be it known that I, LEWIS WARRINGTON CHUBB, a citizen of the United States, and a resident of Edgewood Park, in the county 5 of Allegheny and State of Pennsylvania, have invented a new and useful Improvement in Systems of Control, of which the following is a specification.

My invention relates to wireless telegraphy and more especially to systems of control that are employed in connection with 10 wireless transmission systems.

One object of my invention is to provide a system of control which will maintain a 15 substantially constant load on the source of energy during the signaling and non-signaling periods.

A further object of my invention is to provide a radio transmission system in 20 which the frequency of the alternating component of current in the source of energy may be maintained constant in value during the signaling and non-signaling periods to obtain stable operation.

25 A still further object of my invention is to provide a transmitting system wherein the antenna circuit may be employed as an absorbing circuit, as well as a radiating circuit, thereby permitting the elimination of 30 the expensive separate absorbing apparatus which has heretofore been employed.

In the operation of arc converters, it is highly desirable to maintain the amplitude and frequency of the alternating component 35 of current through the arc substantially constant in order to permit the arc to operate at maximum efficiency.

One system of control for accomplishing the desired result is the absorption-circuit 40 system of control. The system of control just mentioned involves the use of an absorption circuit which may be selectively caused to absorb the energy in the antenna circuit, thereby decreasing the radiation 45 therefrom. In the absorption-circuit system of control, as applied particularly to arc generators, the signals are formed by causing the arc to oscillate either in the main antenna circuit or in an absorbing circuit, 50 depending upon the energy loss in the one or the other circuit being the greater.

One advantage of the last-mentioned system of control resides in the fact that the

period of the radiating system remains constant during the signaling and non-signaling 55 operations.

Another advantage of the absorption-circuit system is that a constant load may be maintained upon the source of energy, which, in the case of arc-converters, causes 60 an increase in the stability and operating efficiency of the arc.

The particular disadvantage of the absorption-circuit system of control, as heretofore known, resides in the fact that expensive apparatus must be employed in the absorbing circuit to render it effective. 65

According to my invention, I provide a control system embodying the absorption-circuit principle of operation, which permits a load of substantially constant amplitude and frequency to be maintained upon the source of energy during the signaling and non-signaling periods and which also permits the elimination of the expensive 75 auxiliary equipment heretofore associated with absorption circuits.

The desired result is accomplished by employing a plurality of radiating antennæ and providing means whereby the antennæ 80 may be operated in parallel during the signaling period, and in series, as a condenser, in an absorbing circuit, during the non-signaling period.

A novel feature of my invention, which I 85 wish to point out, particularly, is the disposition of the absorbing resistor. The resistor is so disposed, with respect to the antennæ, that it becomes effective as an energy-absorbing element only during the non-signaling 90 period.

My invention may best be understood by reference to the accompanying drawings, in which:

The single figure is a diagrammatic view 95 of circuits and apparatus embodying my invention, as applied to wireless transmission systems.

In the drawing, I have shown a source of energy 1, energizing an arc 2 through a pair of choke coils 3. The antennæ system comprises an elevated conductor system 4, alternate wires 5 and 6 of which are connected to down-leads 7 and 8, respectively, to form two independent radiating antennæ 9 and 10. The down-lead 7 is connected to a 100 105

ground conductor 13 through the coupling coil 11 and the arc 2. The down-lead 8 may be connected to either electrode 14 or electrode 15 of the arc 2 by means of a key 16.

5 The key 16 comprises upper and lower stationary contact members 17 and 18 which are connected, respectively, to the arc electrodes 14 and 15 by means of conductors 19 and 20, and coacting movable contact member 21 which is electrically connected to the down-lead 8 and may be actuated, successively, into engagement with the stationary contact members 17 and 18.

10 A resistor 22 connects the two antennæ systems, the connecting points 23 and 24 being equi-potential points when the antennæ 9 and 10 are operating in parallel relation. The resistance of resistor 22 is of such value that it is capable of placing a load upon the 15 source of energy during the non-signaling period comparable to the load thereon during the signaling period.

15 Upon actuating the movable contact member 21 of the key 16 into engagement with the stationary contact member 17, the down lead 8 is connected to the arc electrode 14 to admit of the operation of the antennæ 9 and 10 in parallel.

20 Upon actuating the movable contact member 21 of the key 16 into engagement with the stationary contact member 18, the down lead 8 is connected to the arc electrode 15 of opposite polarity, to include the arc 2 in an absorbing circuit which comprises the arc 25 2, the mutually inductive coils 11 and 12, the down leads 7 and 8, the elevated antennæ 9 and 10, the key 16 and the conductor 20.

25 In operation, upon actuating the co-acting movable contact member 21 into engagement with the stationary contact member 17, the antennæ 9 and 10 are connected in parallel relation, thereby causing a maximum amount of radiation therefrom. With the antennæ 9 and 10 so connected, the frequency of the alternating component of current supplied to the antennæ 9 and 10 is determined by the product $L^1 - C^1$, where L^1 is the inductance of the coils 11 and 12, with the currents flowing through the coils 30 in the same direction, and C^1 is the sum of the individual capacities of the antennæ 9 and 10 to ground. With the antennæ operating in parallel, substantially no current is carried by the resistor 22 which connects 35 the equipotential points 23 and 24 of the antennæ 9 and 10.

40 Upon actuating the co-acting movable contact member 21 into engagement with the stationary contact member 18, the antennæ 9 and 10 are connected in series and caused to function as a condenser in an absorbing circuit, as hereinbefore described. The period of the alternating component of energy through the arc 2 is now determined 45 by the product of $L^2 - C^2$, where L^2 is the in-

ductance of the coils 11 and 12 when the currents therethrough are in phase opposition, and C^2 is the capacitance between the two antennæ 9 and 10.

50 By reason of the fact that C^1 is smaller than C^2 and that L^1 is larger than L^2 , the products $L^1 - C^1$ and $L^2 - C^2$, which determine the frequency of the alternating component of current, may be maintained constant by adjusting either the one or the other 55 of the variables. For example, the variables L^1 and L^2 may be adjusted to the desired value by varying the mutual inductance between the coils 11 and 12. The mutual inductance of the coils 11 and 12 may be varied 60 by adjusting the distance between them.

65 With the key in the position just described, the resistor 22 becomes effective as an energy-absorbing element to maintain a load upon the arc substantially equal to the 70 load thereon during the signaling period.

75 In the drawing, I have shown a system in which alternate wires 5 and 6 of a single large antenna have been connected to form two separate antennæ 9 and 10. It is evident, however, that the arrangement of the antennæ may be modified by further separating them and supporting them individually. Assuming the antennæ 9 and 10 so separated 80 that C^1 equals C^2 , the mutual inductance between the coils 11 and 12 must be substantially zero in order to maintain the frequency of the alternating component of current constant during the signaling and non-signaling periods.

85 Assuming another position in which the antennæ are still further separated, so that, C^2 is greater than C^1 , the connections of one of the coils 11 or 12 must be reversed in order to maintain the product of $L^1 - C^1$ and $L^2 - C^2$ equal.

90 From the foregoing description, it will be seen that my invention provides a system of control of unusual simplicity and ease of operation which admits of the elimination of expensive apparatus heretofore necessary in wireless transmission systems employing the absorption-circuit method of control.

95 While I have shown only one embodiment of my invention in the appended drawing, I do not wish to be restricted thereto, but I desire that only such limitations shall be imposed upon my invention as are set forth in the appended claims.

100 I claim as my invention:

1. In a wireless transmission system, a plurality of radiating antennæ and means whereby said antennæ may be included in an absorbing circuit.

105 2. In a wireless transmission system, a plurality of antennæ and means whereby said antennæ may be caused to function as a condenser in an absorbing circuit.

110 3. In a wireless transmission system, a double antenna, a source of energy therefor

and means whereby said double antenna may function as capacitance in an absorbing circuit.

4. In a wireless transmission system, a double antenna, an energy-absorbing element associated therewith, a source of energy for said double antenna and means for providing an absorbing circuit shunted around said source of energy and including said double antenna as a condenser.

5. In a wireless transmission system, an absorbing circuit comprising a source of energy, a plurality of adjacently-disposed radiating antennæ, an energy-absorbing element associated therewith and means whereby said absorbing circuit may be selectively rendered effective or non-effective to control the radiation of energy from said antennæ.

20 6. In a wireless transmission system, an absorbing circuit comprising a source of energy, a plurality of adjacently-disposed series-connected radiating antennæ, a resistor for connecting said antennæ; the connecting points of said resistor having substantially equal potentials when said antennæ are operating in parallel, and means whereby said absorbing circuit may be selectively rendered effective or non-effective to control the radiation of energy from said plurality of antennæ.

7. In a wireless transmission system, an absorbing circuit comprising a source of energy, a plurality of adjacently-disposed series-connected radiating antennæ, an energy-absorbing element electrically connecting said radiating antennæ and means whereby said absorbing circuit may be selectively interrupted and said radiating antennæ connected in parallel relation.

35 8. In a wireless transmission system, an absorbing circuit comprising a source of energy, a plurality of adjacently disposed series-connected radiating antennæ, an energy-absorbing element, a power-connection between each antenna and said source of energy, each power-connection including a coil, said coils being disposed in mutually inductive relation, and means whereby said absorbing circuit may be selectively interrupted and said radiating antennæ connected in parallel relation.

50 9. In a wireless transmission system, an absorbing circuit comprising a source of energy, a plurality of adjacently-disposed radiating antennæ, an energy-absorbing element, a power connection between each antenna and said source of energy, a coil individual to each power-connection, said coils being mutually inductive, and means included in one of said power-connections whereby said absorbing circuit may be selectively rendered effective or non-effective to control the radiation of energy from said radiating antennæ.

10. In a wireless transmission system, an antenna, a down lead therefor, said down lead containing inductance, a source of energy, a ground connection therefor, a second antenna disposed in electrostatic relation to said first antenna, an energy-absorbing element electrically connecting said antennæ, a down lead for said second antenna, said second-named down lead including an inductance coil, and means whereby said second-named down lead may be successively connected to opposite terminals of said source of energy.

15 11. In a wireless transmission system, an antenna, a down lead therefor, said down lead comprising an inductance coil, a source of energy, a ground connection therefor, a second antenna disposed in electrostatic relation to said first antenna, a down lead for said second-named antenna, said last-mentioned down lead including an inductance coil disposed in mutual inductive relation to said first-named coil, means whereby said last-named down lead may be successively connected to opposite terminals of said source of energy whereby said antennæ may be successively connected in parallel and in series relation, and an energy-absorbing element connecting said antennæ, the points of connection of said element being substantially equipotential when said antennæ are operating in parallel.

20 12. In a wireless transmission system, a plurality of antennæ, a source of energy therefor, and means for electrically connecting said antennæ to said source of energy, said means including a switching device for connecting one of said antennæ to either the one or the other of the terminals of said source whereby said antennæ may be selectively caused to operate in series as a condenser in an absorbing circuit or to operate in parallel as radiating circuits, said means including mutually inductive coils so disposed that the period of said absorbing circuit is equal to the period of said radiating circuits.

25 13. In a wireless transmission system, a plurality of antennæ, a source of energy therefor, a resistor connecting said plurality of antennæ at equipotential points, and means for electrically connecting said antennæ to said source of energy, one of said means including a switching device whereby said antennæ may be selectively caused to operate in series as a condenser in an absorbing circuit or to operate in parallel as radiating circuits, both of said means including mutually inductive coils so disposed that the period of said absorbing circuit is equal to the period of said radiating system with said antennæ operating in parallel.

30 14. In a wireless transmission system, a radiating system comprising a plurality of antennæ and an energy-absorbing element

- connecting said plurality of antennæ at equipotential points.
15. A high-frequency transmission system comprising a plurality of antennæ circuits, a source of high-frequency oscillations and means for operating said antennæ circuits in parallel for radiating energy and in series for absorbing energy substantially without radiation.
- 10 16. A high-frequency transmission system comprising a plurality of antennæ circuits, tuning devices therefor, a source of high-frequency oscillations and means for operating said antennæ circuits in parallel for 15 radiating energy and in series for absorbing energy substantially without radiation, said circuits being so arranged that the frequency thereof is substantially the same for both radiating and absorbing.
- 20 17. A high-frequency transmission system comprising a plurality of antennæ circuits, a source of high-frequency oscillations therefor, means for operating said antennæ circuits in parallel for radiating energy and 25 in series for absorbing energy substantially without radiation, and means whereby the load drawn by said circuits from said source is substantially constant whether energy is radiated or absorbed.
- 30 18. A high frequency transmission system comprising a plurality of antennæ circuits, a source of high-frequency oscillations therefor, connections between said source and said antennæ circuits and means for changing said connections to operate said 35 antennæ circuits in parallel for radiating energy and in series for absorbing energy substantially without radiation.
19. A high frequency transmission system comprising a plurality of antennæ circuits, tuning devices therefor, a source of high-frequency oscillations, connections between said source and said antennæ circuits, means for changing said connections to operate said antennæ circuits in parallel for 40 radiating energy and in series for absorbing energy substantially without radiation, said circuits being so arranged that the frequency is substantially the same for both 45 radiating and absorbing.
20. A high-frequency transmission system comprising a plurality of antennæ circuits, a source of high-frequency oscillations therefor, connections between said source and said antennæ circuits, means for connecting said source to operate said antennæ circuits in parallel for radiating energy and in series for absorbing energy, substantially 50 without radiation, and means whereby the load drawn by said circuits from said source is substantially constant, whether energy is 55 radiated or absorbed.

In testimony whereof, I have hereunto subscribed my name this 18th day of May, 1921.

LEWIS WARRINGTON CHUBB.
